Des. 197,263
Patented Dec. 31, 1963

197,263

COMBINED VENTILATING HOOD AND WARMING COMPARTMENT

Stanley M. Joseph, Glendale, Calif., assignor to Stanthony
Corporation, Los Angeles, Calif., a corporation of
Delaware

Filed Feb. 5, 1963, Ser. No. 73,443

Term of patent 14 years

(Cl. D81—25)

Fig. 1

Fig. 2

Fig. 3

FIG. 1 is a front elevational view of a combined ventilating hood and warming compartment showing my new design;

FIG. 2 is a plan view;

FIG. 3 is an end elevational view;

FIG. 4 is a front elevational view with doors open; and FIG. 5 is an isometric view thereof.

The bottom is substantially plain and unornamented.

I claim:

The ornamental design for a combined ventilating hood

and warming compartment, substantially as shown and described.
